ATTACHABLE GARMENT HOOK

Stuart Gerald Wood, Washington, D. C.

Application March 11, 1954, Serial No. 415,514

8 Claims. (Cl. 248—227)

The following specification relates to improvements in readily attachable garment hooks. It answers the general description of a hook which may be clamped in any selected position along a bar or a rail which in turn may be attached to a wall. Such devices are required to be readily attached in selected positions and then secured when desired against unauthorized removal. They are normally made with two superposed hooks, the upper of which is longer than the lower one, so that garments and hats or the like may be conveniently held.

The present invention has for an object the provision of such a garment hook which may be easily moved from place to place at the will of the user optionally along with the mounting bar or rail.

It is also an object of the invention to provide clamping means by which the hook may be attached by a single operation or movement, specifically like that of a toggle.

Among the objects of my invention is the ability to insure the permanent attachment of the hook if desired so that it cannot be loosened or removed without considerable effort or the use of tools.

The improved article can be manufactured easily by simple operations upon stock material.

Finally the hooks manufactured in accordance with this invention are most economical to make and are cheaply installed by unskilled labor.

Other objects of my invention will be evident from the following description of the preferred form as illustrated on the accompanying drawings in which.

Fig. 1 is a front elevation of the improved garment hook movably clamped to a rail;

Fig. 2 is a vertical section transversely of the rail.

Fig. 3 is a plan view of the same;

Fig. 4 is a front elevation of the hook in open position;

Fig. 5 is a rear elevation of the hook in open position;

Fig. 6 is a front elevation of a modified form in open position and

Fig. 7 is a vertical section of the modified form in clamped position.

As representing the essential features of the invention, I have shown the preferred form in the accompanying drawings and as adapted for attachment to a rail 9. This rail may be either a portion of a movable garment rack or, in the alternative, it may be a bar which is permanently attached to the side wall of a hall, room, clothes closet or the like. It is to be understood that the bar or rail may be put in position wherever it is desired to mount a series of hooks, and may be attached to the wall by nails or screws.

The novel device is built up of three strips of sheet metal or like, rigid material. A back plate or strap 10 is provided with a horizontal or rectangularly disposed foot 11. This back plate is adapted to rest against the front face of the rail 9, with the foot 11 held against the bottom edge of the rail.

A middle strap 12 also made of sheet metal or the like,

is positioned in front of the back plate 10. The middle strap has a hook 13 at its lower portion.

A pivot pin 14 fastens the plate 10 and the strap 12 together at their upper ends, as shown in Fig. 4. The pivot pin has its front surface flush with the front surface of the strap 12.

A front strap 15, made of sheet metal and preferably having a slight resilience, is attached pivotally at its intermediate portion to the middle strap 12 by means of 10 a pivot pin 16.

The pivot pins 14 and 16 are rivets or analogous members which, however, are loose enough to permit the free angular movement of the parts 10, 12 and 15, as shown in Fig. 4.

The upper portion of the strap 15 is bent back to form a claw 17. This claw has a downward and backward slope, as shown in Fig. 5, and may be divided to form two fingers.

The front strap 15 is extended forwardly beyond the hook 13 to form a second hook 18.

The back plate 10 is drilled at an intermediate point to provide a countersunk hole 19. The middle strap 12 is also punched out to form a hole 20, which can be brought into registration with the hole 19 when the plate 10 and the strap 12 are in parallelism. The hole 20 has a protuberance 21 projecting rearwardly, which will fit in the countersunk portion of the hole 19. This forms a detent to hold the plate and strap together and in alignment. The middle plate forms a toggle of the two parts, so that the foot 11 and the claw 17 are clamped against the opposite edges of the rail 9.

While the parts are thus satisfactorily clamped on the bar subject to removal, a wood screw 22 can be passed through the holes 19 and 20 and fastened within the rail 9 to hold the parts against unauthorized detachment.

In the form shown in Figs. 6 and 7, the back plate 10 has a hole 23 at its upper end, as already described. It also has the countersunk hole 19, above described. The middle strap 24 is provided with a hole 25 in its upper end. 40 This hole has a rim 26 which is passed through the hole 23 and forms a hollow rivet when peened outwardly. This fastening, however, permits the plate 10 and strap 24 to be tilted, as shown in Fig. 6.

The middle strap 24 has a lower hole 20 with a protuberance 27 fitting within the countersink 19.

The front strap 28 has a hole 29 in an intermediate portion. The middle strap 24 has an integral flange 30 which is struck up to form a hollow rivet received within the hole 29. This hollow rivet is peened outwardly, as shown in Fig. 7, and provides a pivotal bearing for the front strap 28.

The rim 26 and the flange 30 may be protuberances or studs and not necessarily perforated or hollow.

The upper portion of the front strap 28 is bent backwardly and downwardly to provide a bearing surface as shown at 31, resting upon the upper edge of the bar 9. The strap 31 is bent upward to form a vertical extension 32. A horizontal ledge 33 is bent forwardly to provide a rest.

When the garment hooks have been mounted upon one or more rails 9, for example on the back and sides of a clothes closet, they form supports for a shelf 34, as indicated in Fig. 7.

In this modification the toggle action of the middle strap 24 and its hook 13 serves to fasten the attachment to the bar 9, with the holes 20 and 27 in registration. A screw 22 can then be fastened through the holes and into the bar to make the attachment permanent.

The horizontal ledge 33 may be perforated as shown in Fig. 7 to permit screw-threaded attachment of the shelf 34.

In each form of the invention the rail 9 may be either

already a part of the wall or may be furnished with the hooks and attached as a preliminary step. The several hooks are then successively located on the rail and clamped on it by a swinging toggle movement of the middle part 12 or 24. This clamps the foot and upper parts 17 or 31 on the edges of the bar. The latter may have its upper edge sloped backwardly for better engagement with the member 17 and likewise the bottom edge can be sloped backwardly to be engaged by the foot 11 as shown in Fig. 7.

The hooks are held in clamped position by the interfitting parts 19 and 21, or 27 as the case may be. However, this can be made permanent by use of screws 22. The hooks can be spaced as desired. They may be individually removed by rocking the middle straps and loosening the toggle clamp.

The invention has been illustrated by way of example and described above. However, it will be apparent that numerous changes can be made in material and proportions within the scope of the appended claims.

What I claim is:

1. A garment hook comprising a back plate having a rearwardly extending foot, a middle strap having a hook extending forwardly in the same vertical plane as the said foot, said back plate and middle strap having a pivotal connection at their upper ends, a front strap pivotally connected to the middle strap below the said connection and in the same vertical plane, a hook extension at the lower end of the front strap and a claw on the upper end of the front strap spaced above the foot and in the same vertical plane.

2. A garment hook comprising a back plate having a rearwardly extending foot, a middle strap having a hook extending forwardly in the same vertical plane as the said foot, a pivot pin connecting the said plate and strap at their upper ends, a front strap pivotally connected to the middle strap below the pivot pin and in the same vertical plane, a hook extension at the lower end of the front strap and a claw on the upper end of the front strap spaced above the foot and in the same vertical plane.

3. A garment hook comprising a back plate having a rearwardly extending foot, a middle strap having a hook extending forwardly in the same vertical plane as the said foot, a pivot pin connecting the said plate and strap at their upper ends, a front strap, a second pivot pin connecting the front strap and the middle strap below the first mentioned pivot pin and in the same vertical plane, a hook extension at the lower end of the front strap and a claw on the upper end of the front strap spaced above the foot and in the same vertical plane.

4. A garment hook comprising a back plate having a rearwardly extending foot, a middle strap having a hook extending forwardly in the same vertical plane as the said foot, said back plate and middle strap having a pivotal connection at their upper ends, a front strap pivotally connected to the middle strap below the said connection and in the same vertical plane, a hook extension at the lower end of the front strap, said back plate and middle strap being given complementary configurations for hold-

ing them together in parallelism, and a claw on the upper end of the front strap spaced above the foot and in the same vertical plane.

5. A garment hook comprising a back plate having a rearwardly extending foot, a middle strap having a hook extending forwardly in the same vertical plane as the said foot, said back plate and middle strap having a pivotal connection at their upper ends, a front strap pivotally connected to the middle strap below the said connection and in the same vertical plane, a hook extension at the lower end of the front strap, the back plate being formed with a countersunk hole, the middle strap having a hole with a rearwardly projecting rim fitting into the countersunk hole of the back plate, and a claw on the upper end of the front strap spaced above the foot and in the same vertical plane.

6. A garment hook comprising a back plate having a rearwardly extending foot, a middle strap having a hook extending forwardly in the same vertical plane as the said foot, said back plate and middle strap having a pivotal connection at their upper ends, a front strap pivotally connected to the middle strap below the said connection and in the same vertical plane, a hook extension at the lower end of the front strap, said back plate being formed with a hole, the middle strap being formed with a hole registering with the hole in the back plate, a fastening means for holding said holes in registry and a claw on the upper end of the front strap spaced above the foot and in the same vertical plane.

7. A garment hook comprising a back plate having a rearwardly extending foot and a transverse round hole in its upper portion, a front strap having a hook on its lower end and a transverse round hole in its intermediate portion, a middle strap having two integral portions projecting in opposite directions and each pivotally held in one of said holes, and a claw on the upper end of the front strap spaced above the foot.

8. A garment hook comprising a back plate having a rearwardly extending foot, a middle strap having a hook extending forwardly in the same vertical plane as the said foot, said back plate and middle strap having a pivotal connection at their upper ends, a front strap pivotally connected to the middle strap below said connection, a hook extension at the lower end of the front strap, a clamp on the upper portion of the front strap spaced above the foot and in the same vertical plane and an integral shelf support extending upwardly from the end of said clamp.
